UNITED STATES PATENT OFFICE.

HAROLD EDWARD NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A HANDLE FOR SPOONS OR ANALOGOUS ARTICLES.

50,792.

Specification for Design.

Patented May 15, 1917.

Application filed March 9, 1917. Serial No. 153,767. Term of patent 7 years.

To all whom it may concern:

Be it known that I, HAROLD EDWARD NOCK, a citizen of the United States, residing at Newburyport, in the county of Essex and State of Massachusetts, have invented a new, original, and ornamental Design for a Handle for Spoons or Analogous Articles, of which the following is a specification, reference being had to the accompanying drawing, forming a part thereof.

In the accompanying drawing, Figure 1

is a representation of the front of a spoon showing the new design; Fig. 2 is a representation of the back of the spoon showing the new design, and Fig. 3 is a cross-section of the handle shown in Figs. 1 and 2, taken at the dot and dash line on Fig. 1.

I claim:

The ornamental design for a handle for spoons or analogous articles substantially as shown, or any colorable imitation thereof.

HAROLD EDWARD NOCK.
